(57) **CLAIM**

The ornamental design for a hex driver stripper sander, as shown and described.

DESCRIPTION

FIG. 1 is a top perspective view of a hex driver stripper sander showing our new design;

FIG. 2 is a top plan view thereof;

FIG. 3 is a typical side elevation view thereof; and,

FIG. 4 is a bottom plan view thereof.

The broken lines in the drawings illustrate portions of the surface perimeter of discs as being a representation for an abrasive surface material of the hex driver stripper sander and broken concentric lines on the bottom of FIG. 4 form no part of the claimed design.
